UNITED STATES PATENT OFFICE

HJALMAR BERNHARD OHLSON, OF STOCKHOLM, SWEDEN

PAGE LOCK FOR PRINTERS' FORMS

Application filed January 11, 1930, Serial No. 420,218, and in Sweden February 9, 1929.

Compositors' frames, so-called page locks, are known for locking the set-up type, which frames consist of separate parts having cut-out portions in which locking noses engage.

5 The construction is such that, when fitted together alternately, a frame is formed having play in each corner. This play is however kept comparatively small in the known page locks merely for the purpose of being able

10 to carry out slight paragagation.

In order to overcome the existing objections a device is provided according to the invention for holding together pages for compositors' frames and has for its object 15 the obviating of the complicated and time-wasting cording of the pages so that when carrying out corrections and lifting out type or rows of type the frame parts can remain in engagement. The invention therefore

20 renders it possible to retain the known play as large as possible according to these requirements. The corners of the frame parts are connected according to the invention by similar elements which are so arranged, that 25 they are inserted in the corresponding spaces after the fitting together of the frames, where they remain during the printing.

An embodiment of the invention is illustrated by way of example in the accompanying drawings in which

30 Fig. 1 is a top plan view of a side bar of the frame.

Fig. 2 shows a built up frame with the parts pushed together.

35 Fig. 3 is a similar view to Fig. 2 the parts being pulled apart.

Fig. 4 is a top plan view of joint between two parts.

Fig. 5 shows a spreading pin.

40 Fig. 6 shows in perspective view a page of set-up type to be held by a frame according to the invention.

The frame according to the invention consists of known side bars *a*. Each side bar 45 has a hook shaped cut out portion *b* of hook-shaped cross section at one end and a nose *c* also hook shaped. When fitting together the separate side parts to form a frame, the locking nose *c* is inserted in the cut out portion *b* (Fig. 4). The locking nose and the

cut out portion are so shaped that they do not form a tight joint but a space *d* is formed in each corner connection, as shown in Fig. 2. Owing to this play it is possible, to pull apart to all sides the four bars forming a 55 frame, as shown in Fig. 3, or to push them close together as shown in Fig. 2. A spreading pin *e*, Fig. 5, or similar element, is inserted in each of the spaces *d* formed in the corners of the built up frame, which pins 60 hold the parts of the frame in their pushed together position. The frame proper can consist of side bars, each consisting of one piece. These side bars may however, according to the invention and as shown in Figs. 65 3 and 6, consist of two or more parts *a*, *a'* the locking noses and cut out portions of which are so constructed, that the parts *a*, *a'* when fitted together in the longitudinal direction lock tightly together. 70

I claim:

A page lock for printers' forms, comprising in combination side bars having at one end a hook shaped cut out portion, a hook shaped extension at the other end of said side 75 bar of the same size as said cut out portion adapted to loosely engage in the cut out portion of an adjacent bar so that the two bars form a corner, and spring pins adapted to be inserted in the free spaces left between said 80 hook shaped extensions and said hook shaped cut out portions adapted to clamp said bars tightly together during the printing operation.

In testimony whereof I affix my signature. 85
HJALMAR BERNHARD OHLSON.
